CLAIM

The ornamental design for a toilet caddy, as shown and described.

DESCRIPTION

FIG. 1 is a front perspective view of a toilet caddy which embodies the design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken-line disclosure in the views is understood to represent a portion of the article in which the claimed design is embodied, but which forms no part of the claimed design.
